UNITED STATES PATENT OFFICE.

STANLEY J. JEMERZYCKI, OF CHICAGO, ILLINOIS.

POWDER-DUSTING BRUSH.

Application filed March 23, 1925. Serial No. 17,553.

This invention relates to powder dusters and more particularly to a magazine brush, especially adapted for use by barbers and hairdressers for dusting talcum powder on the face or neck.

The object of the invention is to provide a practical and suitable brush for the purpose set forth, and embodying several novel features of construction and design calculated to increase its utility and to overcome the disadvantages of brushes of a similar character that have appeared on the market from time to time.

A preferred embodiment of the brush is disclosed in the accompanying drawings, in which—

Figure 1 is a general view in elevation of the brush embodying the invention;

Figure 2 is a similar view of the brush with the body portion shown in section;

Figure 3 is a cross-sectional view taken on line 3—3 of Figure 2, and showing the shut-off valve in open position, and

Figure 4 is the same view showing the valve in closed position.

As clearly shown in the drawings, the body of the brush consists of a hollow cylindric shell 1, surmounted by a tapered handle 2, at one end. At the opposite end is the brush proper 3, consisting of a mass of bristles supported in a circular base or support 4, abutting against the end of the body.

The lower end portion of the body is in the form of a cap 5 separated from the rest of the body by a screw-threaded connection and normally forming a closure for the magazine.

The cap has a marginal flange 5^a extending endwise, its edge seating around the periphery of the circular support 4 for the brush bristles. Located centrally of the bottom cap 5 is a metal sleeve 6 forming a tubular extension projecting beyond the edge of the flange, and terminating in a threaded end and engaging a threaded aperture at the center of the bristle support 4, with the edge thereof in abutting engagement with the edge of the flange 5^a.

Within the sleeve 6 is a smaller rubber tube 7, communicating with the magazine at its upper end and extending some distance beyond the bristle support and terminating at approximately the center of the mass of bristles.

Between the bottom cap 5 and the bristle

support 6 is a space or cavity 8 in which is located the valve or tube closure for controlling the discharge of the powder from the magazine above. As clearly shown in Figures 2 and 3, a transverse slot 9 is cut in sleeve 4, just below the bottom cap, thus exposing a portion of the rubber tube within.

Lying in the plane of the slot is a tube closure member 10 consisting of a length of spring wire having a loop near one end which is held by a screw 11 anchored in the bottom cap 5, with a free end portion 10^a bearing against the inner surface of the surrounding wall of the cavity. The remaining portion of the spring extends across the slot 9, being provided at that point with a U-shaped bend 12 which projects toward the rubber tube. Just beyond the slot the wire is bent at right angles and is embedded at its end in a button 13 supported in the flange 5^a.

As clearly shown in Figure 3, the closure member normally acts to close the tube by forcing the U-shaped projection against the tube and pinching it closed. By pressing the button, the desired quantity of powder is released from the barrel magazine and discharged into the mass of bristles through the tube, and thus distributed evenly and lightly over the surface by the usual brushing motion. To replenish the magazine it is only necessary to unscrew the lower part of the brush from the body.

If desired, the rubber tube may be provided with additional openings 7^a at different points throughout its length, thus obtaining a more general distribution of the powder throughout the mass of bristles.

There are several novel features in the construction of the brush which may be mentioned. The use of a soft and flexible rubber tube has a distinct advantage, in that it may be extended axially of the brush far enough to discharge the powder near the end of the bristles, and at the same time yield with the bristles so that its presence is not noticeable in the use of the brush.

A further feature is the simple and practical method of controlling the discharge of the powder from the magazine, namely, by the spring which merely pinches the rubber tube to close the passage.

The method of assembling the brush is also advantageous in that the bristle support is quite independent of the body and hence,

may be readily removed and replaced by a new brush without disturbing the remaining parts of the brush which are not subject to the same amount of wear.

5 Having set forth the construction of the brush and the advantages thereof, I claim as my invention:

1. A brush of the character described, comprising a handle having a hollow body 10 open at one end, a screw cap closing the end of said handle, and provided with a marginal flange and a central tubular extension, a brush member having threaded engagement with the end of said tubular extension 15 and seating at its periphery against said flange, a pliable tube extending through said tubular extension and means for closing said tube comprising a spring actuated member engaging said tube through a slot in said tubular extension.

2. A brush of the character described, comprising a hollow handle open at one end, a cap removably mounted in the end of said handle and having a tubular extension projecting axially therefrom, a brush member 25 spaced from said cap and engaging the end

of said extension, a tube of pliable material extending through said tubular extension, the latter being provided with a slot exposing a portion of said tube and a spring actuated member normally bearing against said tube to close the passage therethrough.

3. A brush of the character described, comprising a handle having a hollow body 30 open at one end, a screw cap closing the end of said handle, and provided with a marginal flange, and a central tubular extension and a brush member comprising a bristle support having a central aperture in threaded engagement with the end of said tubular 35 extension and seating at its periphery against said flange, a pliable tube extending through said tubular extension and beyond said bristle support, a spring-actuated closure member operable through a slot in 40 said extension to normally pinch said tube, and a button mounted in the wall of said body and connected with said closure member.

Signed at Chicago, Ill., this 13th day of 50 March, 1925.

STANLEY J. JEMBRZYCKI.
